UNITED STATES PATENT OFFICE.

CHARLES WILLIAM WIRTH, OF MILLVALE, PENNSYLVANIA.

TOY RAILROAD-GATE SET.

1,415,753.

Specification of Letters Patent.

Patented May 9, 1922.

Application filed September 10, 1920. Serial No. 409,311.

To all whom it may concern:

Be it known that I, CHARLES W. WIRTH, a citizen of the United States, residing at Millvale, in the county of Allegheny and State of Pennsylvania, have invented a new and useful Toy Railroad-Gate Set, of which the following is a specification.

This invention relates to toy railroad gate sets.

- 10 The object of the invention is to provide a device of this character which is automatically operated by a toy train so that the gates close in advance of the train and open only after the train has passed.
- 15 Another object is to provide toy railroad gates whose construction is such that they simulate very closely the gates which are usually employed at steam railroad crossings.
- 20 Further objects are to provide an easily manufactured and entertaining toy and one which will be attractive in appearance so that it may be used in window displays by merchants, and whose construction is relatively simple and inexpensive.

The invention will be best understood from a consideration of the following detailed description taken in connection with the accompanying drawing forming part 30 of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

Fig. 1 is a top plan view of the embodiment of the invention.

Fig. 2 is a side elevation of the same.

Fig. 3 is a vertical cross-sectional view on an enlarged scale.

Fig. 4 is a cross section on line 4—4 of Fig. 3.

Figs. 5, 6 and 7 are detail views of the trip mechanism for causing lowering of the gates in advance of the train.

The numeral 10 denotes the base of the toy set, which base has a central channel-way 12 for receiving the toy tracks 11. The track employed is of the third-rail type whereby electric trains may move over the same. The base 10 provides a housing for nearly all the moving parts of the mechanism for operating the gates, the few parts

not housed by the base being readily slideable underneath the three rails of the track without interference. An elongated slot 13 is provided on the base 10 for a purpose to 60 be described.

Mounted upon the base so as to swing from a vertical to a horizontal position, and vice versa, are four gates 14 which are constructed to closely simulate the ordinary 65 steam railroad gates employed at grade crossing in cities. These gates 14 have swingably mounted stop rods 15 for preventing the gates from striking the base as they move downwardly to closing position. They 70 also have the usual counterweights 16.

Gate supports 17, in the nature of a housing for the gate-operating mechanism, are provided. Raised portions 18 of the base 10 join with the housings 17. Alined apertures 75 19 are provided on two opposite faces of the gate support 17, and through these apertures a gate pivoting rod 20 extends. Each gate 14 embraces the corresponding housing 17 and is united to the ends of the rod 20. A 80 crank arm 21 is formed intermediate of the rod 20 and to this crank arm a link 22 is joined. The link 22 extends downwardly through the housing 17 and is pivotally connected at its lower end to a swinging platform 23. The platforms have raised flanges 24 on both longitudinal edges, these flanges providing guides for a slidble weight 26. The platforms are supported at mid-points above the bottom of the base by arms 25. 90

The weights 26 have slots 27, and bars 28 are pivotally mounted within said slots. The platforms 23 have longitudinally-extending slots 23^a for receiving the bars 28 when the platforms rise at that end adjacent said bars. 95 Each bar 28 is pivotally connected with a sliding rod 29 passing through guiding bores in angle pieces 30 secured to the base.

In the toy set illustrated in the drawing, two railroad gates, each consisting of a 100 pair of gates 14, are shown. The present invention is not limited to any particular number of gates, the operating mechanism being applicable to any number of gates. In order that the opposite gates may 105 be raised and lowered together, the opposite slide rods 29 are united by a cross-piece 31; thus the two rods 29 operate in unison.

The mechanism by which movement of the train effects the proper movement of the 110 gates will now be described. Pivoted to the base, as at 33, is a bar 32, pivotally connect-

ed at its ends to links 34. A link rod 35 is pivotally connected to the end of one of the links 34 and is in turn secured to the cross-piece 31. The rod 35 has considerable length, extending parallel with the track two feet or more. The extremity of the rod 35 is bent at right angles, as indicated at 36, and is joined to a pair of flanges 40 provided on a slide 39. The slide moves in a guideway 10 38 provided on a plate 37 which may form an extension of the base or may be secured to the track, floor or other support. A pin 41 passes between the flanges 40, and a flat spring 42 is secured at one end to the slide 15 39 and extends underneath the end 36 of the rod 35. The opposite end of the spring 42 presses upon one arm of a trip 43, pivoted, as at 45, to swing between the flanges 40. The spring 42 tends to hold the other arm of the 20 trip in a vertical position, as shown in Fig. 5. This last-mentioned arm has a right-angular extension 44 providing convenient means which a lug or projection on the engine may strike.

25 A trip entirely analogous to the one shown in Figs. 5, 6 and 7, is provided at the opposite end of the base 10, with the trip guided by the slot 13 and slideable the length thereof. The first-described trip is designed 30 to make the gates lower simultaneously in advance of the passage of the train over the toy set. The trip, which is movable in the slot 13, is designed to be engaged by a lug or projection on the last car of the toy train, 35 whereby the gates will be raised only after the train has passed completely over the set. The direction in which the train must travel relative to the device of the invention is indicated by the arrowhead in Fig. 1.

40 When either extension arm 44 is struck, the trip 43 will slide in its guideway and thus pull the respective links 34, afterwards bending and giving way. The two links 34, being joined together and being connected to the cross-piece 31, it will be clear that movement of either trip will cause sliding of the cross-piece 31 longitudinally of the base 10, thus effecting simultaneous longitudinal sliding of the rods 29. Movement 45 of the rods 29 will cause the weights 26 to move to one end or the other of the platforms 23. The housings for the raised portions 18 of the base 10 will provide room for sliding of the weights 26 in the base and 50 along the platform.

55 As will be noted from Fig. 3, the disposition of the crank arms 21, links 22, and platforms 23, is such that when the sliding weights 26 move as a pair to the left, as viewed in this figure, the gates 14 will rise, while if the weights are slid to the right, the gates will simultaneously fall until they assume the position illustrated in Fig. 2.

60 The device is adapted to provide much entertainment for children, is designed so as

to aid in making an effective window display by dealers in electrical toys, and has a mechanism which, because of its extreme simplicity, is not likely to get out of order. Other railroad gates are operated by hydraulic or air pressure, or even by electrical power, and are expensive to build, besides being liable to get out of order. The provision of sliding weights on a swinging platform, as in the present invention, makes the 75 set easy to build and simple to repair.

What is claimed is:—

1. In a device of the class described, a gate mounted to swing on a horizontal axis, a pivoted platform connected to the gate so 80 that the gate and platform swing together, said platform having guiding means, a weight slideable on the platform and guided by said means, and mechanism for shifting the position of the weight. 85

2. In a device of the class described, a gate mounted to swing about a horizontal axis, and means for causing said swinging, said means including a pivoted platform, a weight slideable on the platform to either side 90 of the pivot thereof, means connected to the weight for effecting sliding of the same, and means joining the platform to the gate so that the latter swings synchronously with the platform. 95

3. In a device of the class described, a pair of gates mounted to swing about horizontal axes, the two gates extending in opposite directions toward each other, a supporting rod secured to each gate, a pivoted platform for each gate, a link and crank connection between one end of each platform and the respective gate supporting rod, a weight slideable on each platform, the two platforms always having the same inclination, 100 means connecting the two weights together, and means whereby the weights are slid. 105

4. In a device of the class described, pairs of gates oppositely mounted to swing on horizontal axes, a swingably mounted platform beneath each gate, mechanism connecting each platform with its gate whereby a relatively small swinging of the former causes a swing of the latter through an arc of at least ninety degrees, and means for simultaneously shifting the center of balance of the platforms whereby all the gates rise and fall together. 115

5. In a device of the class described, a gate mounted to swing on a horizontal axis, a 120 pivoted platform located near the gate and connected thereto so that the gate and platform must swing together, said platform having guiding flanges upstanding from its longitudinal edge, a weight slideable on the 125 platform between the flanges, and mechanism for shifting the positions of the weight. 130

6. In a device of the class described, pairs of gates oppositely mounted to swing on a

horizontal axis, the gates of each pair extending toward each other, a supporting rod joined to each gate, a crank joined to said rod, a link connected with the crank at one end, a swinging platform connected to the other end of the link, a weight slideable on each platform, guiding means on the platform for the weight; rods connecting

the weights on the platforms of each pair of gates, and means connecting the rods together so that the weights all move together.

In testimony, that I claim the foregoing as my own, I have hereto affixed my signature.

CHARLES WILLIAM WIRTH.
